UNITED STATES PATENT OFFICE.

CARL L. JAEGER, OF MAYWOOD, NEW JERSEY.

RECORDING DEVICE.

No. 863,281.

Specification of Letters Patent.

Patented Aug. 13, 1907.

Application filed January 16, 1906. Serial No. 296,284.

To all whom it may concern:

Be it known that I, CARL L. JAEGER, a citizen of the United States, and a resident of Maywood, in the county of Bergen and State of New Jersey, have invented certain new and useful Improvements in Recording Devices, of which the following is a specification.

My invention relates to improvements in recording devices and especially to recording compasses, such as disclosed in my prior patents #472,124, #533,902, 10 #556,987, #639,053; and has for its object to simplify the general construction of the apparatus therein disclosed and particularly to arrange the parts so as to permit of the simultaneous observation of both record sheet and compass card.

15 For this purpose my invention consists essentially of a compass needle suitably mounted, and carrying a compass card and a spiral conductor; a record sheet suitably supported and visible beneath said card, means to move said record sheet; a radial conductor beneath said 20 record sheet; means to cause a spark to pass between said spiral conductor and said radial conductor, and a transparent cover to which said compass needle, card and spiral conductor are loosely attached and to which they may be locked when it is desired to remove or re- 25 place the record sheet.

The nature of my invention will be best understood in connection with the accompanying drawings in which—

Figure 1 is a top view of my improved compass, showing both the compass card and the record sheet. Fig. 2 30 is a vertical section of the apparatus. Fig. 3 is an enlarged sectional and plan view of the support for the record sheet. Fig. 4 is a diagrammatic view showing the various electrical connections.

35 Similar characters of reference designate corresponding parts throughout the several views.

Referring now to the drawings, 10 indicates a compass needle provided with the usual jewel bearing and mounted upon the pivot shaft 11. Carried by this needle is a frame work 12 supporting an annular compass card 13 of the usual type, forming with the needle 10 a compass. Rigidly secured to the arms of the frame work 12 is a conductor 14 bent in the form of an Archimedean spiral. The pivot shaft 11 is 45 centrally mounted within an insulating shaft 15 passing through the two frame plates 16 and 17. These plates are held together by means of a number of posts 18 and 19 and screw caps 20. Between these plates is mounted a clock mechanism, not shown, but 50 indicated by the wheel 21, mounted upon the driving shaft 22, which passes through and projects above the upper frame plate 16. A pinion 23 carried by the portion of the shaft 22 above the frame plate 16 engages a gear wheel 24 keyed to the hub 25, causing it to rotate 55 about the sleeve 26 on the insulating shaft 15. This

hub 25 is constructed with a top supporting flange, as shown in Figs. 2 and 3, and which is provided with a number of unequally spaced pins 27 which are adapted to secure a record sheet 28 supported by the said flange directly below the lower edge of the spiral conductor 60 14 and concentric therewith and adapted to share the movement of the hub 25. I prefer to space these pins unequally, as shown, so that it is impossible to incorrectly place the record sheet upon the supporting flange; and allowing the record sheet itself if properly graduated to indicate the time in conjunction with the usual lubbers-line or a separate indicating pointer.

Directly beneath the record sheet 28 is adjustably mounted a conductor 29 which I term the radial conductor and which is usually placed parallel to the keel 70 and participates in the movement of the vessel; and is radial with respect to said compass, spiral conductor and record sheet and so placed that the record sheet is interposed between it and the spiral conductor 14 as shown in Fig. 2. The spiral conductor 14 thus crosses 75 or intersects, during the movement of the compass, the radial conductor 29 at various points, each point of intersection corresponding to a particular point of the compass.

In addition to the spiral conductor 14, I have shown 80 three other conductors, terminating in points 30, 31, and 32, placed directly above the record sheet 28 and radial conductor 29 and mounted between two insulating plates 33 and 34 and carried out of the apparatus by the wires 35, 36, and 37 through three insulating 85 shafts 38, 39, and 40. These points are adapted to record the time at which certain operations take place: for example to secure a record of the log, the revolutions of the engine and any signals to which they may be connected such as a whistle, etc. A spark is caused 90 to pass between these points or the spiral, and the radial conductor 29 when the corresponding circuit is closed and a perforation is thus made in the record sheet 28 which lies between, and a permanent record 95 is obtained.

The posts 19 above the upper frame plate 16 carry a rim 41 to which is hinged an angle piece 42 carrying a transparent plate such as the glass plate 43 held therein by means of the split spring-ring 44. Centrally disposed with respect to this glass plate 43 and attached 100 to it are two metallic plates 45 and 46, the one above and the other below the said glass plate and the lower one carrying a spring piece 47. The lower arm of the spring piece 47 is adapted to receive the neck 48 of the compass bearing stud 49 thereby loosely attaching the 105 compass needle, card and spiral conductor to the glass cover 43 but normally allowing the said stud to move freely therein. A thumb screw 50 projecting above the glass plate and working in a thread of the bushing 51 is attached to the lower arm of the spring 47 and as 110

it is turned raises or lowers the said spring. The compass stud is thus also raised by the lower arm shoulder-ing against the head of the said stud and thereby carry-ing it and the compass needle. 10, card 13 and spiral 5 14 off their supporting pivot shaft 11 raising them until the head of the bearing stud 49 is held against the block 52 fastened to the upper and fixed arm of the spring 47. The compass needle 10, card 13, and spiral 14 thus become held against the glass cover 43 and the 10 whole may be turned up with the cover allowing the insertion or the replacing of the record sheet. The cover may then be turned down, the thumb screw turned back releasing the compass needle, card and spiral, which again assume their proper positions. In 15 place of the means shown to lock the said compass needle, card and spiral to the cover I may of course use other means such as means to automatically lock the compass needle, card and spiral upon lifting the cover, and I do not wish to restrict myself to any par-ticular means. 20

In Fig. 4 I have shown diagrammatically the elec-trical connections. Current is derived from a dynamo 53 through the mains 54 and 55. An electro-magnet 56 is shunted across these mains as shown and is adapted 25 to automatically throw into circuit the emergency battery 57, should the circuit from the dynamo fail. Four spark coils 58, 59, 60 and 61 are shown controlling respectively the compass record, the signal record, the revolution record, and the log record. Into one of the 30 mains 62 or 63 leading to the spark coil 58 I have indi-cated a time-controlled circuit closer 64 inserted. This device is adapted to periodically close the primary circuit of the spark coil and thereby cause a spark to periodically pass between the spiral conductor 14 35 and the radial conductor 29 puncturing the record sheet 28 and making a permanent record thereon. I prefer to employ the above circuit closer and record a series of perforations. The other primary coils are respec-tively connected to and controlled by signals, revolu-tion counter and a log which are adapted to close the 40 said primary circuits. As soon as these primary cir-cuits are closed, a current is induced in the correspond-ing secondaries and causes a spark to jump between the radial conductor and the respective points 30, 31, 45 and 32, and thereby puncture the record sheet 28. It is evident that a similar recording device may like-weise be employed to record the movements of a mag-netic dipping needle or the movements of other rotat-able indicators, provided slight structural changes be 50 made. Further, by calibrating the record sheet also upon the reverse side and properly indicating the times, this sheet may serve as a valuable aid in determining the return course of a ship.

What I claim as new and desire to secure by Letters- 55 Patent of the United States is:—

1. In a recording device: a compass needle suitably mounted and carrying a compass card; a spiral conductor carried by said compass needle and card; a carrier for a record sheet beneath said compass needle, card and spiral 60 conductor; and a cover to which compass needle, card and spiral conductor are loosely attached and to which they may be locked in such a manner that the said compass

needle, card and spiral conductor may be raised with said cover when it is desired to remove or replace the sheet.

2. In a recording device: a compass needle suitably 65 mounted and carrying a compass card; a spiral conductor carried by said compass needle and card; a cover to which said compass needle, card and spiral conductor are loosely attached; and means adapted to lock said compass needle, card and spiral conductor to said cover.

3. In a recording device: a compass needle suitably mounted and carrying a compass card; a spiral conductor carried by said compass needle and card; a cover to which said compass needle, card and spiral conductor are loosely attached; means adapted to lock said compass needle, card and spiral conductor to said cover; means to sup-70 port and move a record sheet beneath said compass needle, card and spiral and readable therethrough; a radial conductor beneath said record sheet; and means to cause a spark to pass between said spiral conductor and 80 said radial conductor.

4. In a recording device: a compass needle suitably mounted and carrying a compass card; a spiral conductor carried by said compass needle and card; a hinged trans-parent cover above said compass card to which said 85 compass needle, card and spiral conductor are loosely attached; means to lock said compass needle, card and spiral conductor to said cover; means to support and move a record sheet beneath said compass needle, card and spiral and readable therethrough; a radial conductor beneath said record sheet; and means to cause a spark to 90 pass between said spiral conductor and said radial con-ductor.

5. In a recording device: a compass needle suitably mounted and carrying an annular compass card; a spiral 95 conductor carried by said compass needle and card; a cover to which said compass needle, card and spiral conductor are loosely attached; means adapted to lock said compass needle, card and spiral conductor to said cover; means to move a record sheet beneath said compass 100 needle, card and spiral conductor and readable there-through; a radial conductor beneath said record sheet; and means to cause a spark to pass between said spiral conductor and said radial conductor.

6. In a recording device: a compass needle suitably mounted and carrying an annular compass card; a spiral conductor carried by said compass needle and card; a cover to which said compass needle, card and spiral conductor are loosely attached; means adapted to lock said 105 compass needle, card and spiral conductor to said cover; means to support and rotate a record sheet beneath said compass needle, card and spiral conductor and readable therethrough; a radial conductor beneath said record sheet; a number of conductors above said record sheet and directly 110 above said radial conductor; means to cause a spark to 115 pass between said spiral conductor and said radial conductor; and means to cause a spark to pass between said conductors above the radial conductor and the said radial conductor.

7. In a recording device: a compass needle suitably 120 mounted and carrying an annular compass card; a spiral conductor carried by said compass needle and card; a non-magnetic movement; a hub adapted to be driven by said movement and having a flange provided with un-equaly spaced pins, said flange and pins being adapted 125 to support and secure a record sheet beneath said compass needle, card and spiral conductor and readable therethrough; a radial conductor beneath said record sheet; and means to cause a spark to pass between said spiral conductor and said radial conductor.

Signed at New York, Manhattan borough, in the county of New York, and State of New York, this 15th day of January, A. D. 1906.
